UNITED STATES PATENT OFFICE.

FRANK JUTRASCH, OF MILWAUKEE, WISCONSIN.

COOLING-RADIATOR.

1,250,187.

Specification of Letters Patent. Patented Dec. 18, 1917.

Application filed April 24, 1916. Serial No. 93,054.

To all whom it may concern:

Be it known that I, FRANK JUTRASCH, a citizen of the United States, and resident of Milwaukee, in the county of Milwaukee and 5 State of Wisconsin, have invented new and useful Improvements in Cooling-Radiators, of which the following is a description, reference being had to the accompanying drawings, which are a part of this specification.

10 The invention relates to radiators for cooling the circulating water or other fluid used for reducing the temperature of the cylinders of an internal combustion engine, and is more particularly designed for use on 15 automobiles.

At present the common practice in radiator construction is to form the water and air passages by using plates which are soldered or otherwise rigidly secured to 20 together and to the radiator tank to form a concrete whole. Considerable difficulty with radiators of this kind arises when, through some cause, a leak occurs, for in such a case it becomes necessary to partially or wholly 25 dismantle the radiator to repair the leak. It is the essential object of the present invention to obviate this difficulty by providing a radiator which is made up of a plurality of separate independent radiator units which 30 can be easily assembled together to form the radiator and in which any one of the units may be readily removed and replaced if a leak occurs, or if a new unit is not available the remaining units may be assembled to 35 constitute the radiator.

A further object of this invention is to provide a radiator which may be standardized, that is, by making the radiator of independent radiator units of different sizes, 40 these units may be kept in stock by the dealers and make it easy for a car owner to repair his radiator, if a leak occurs, by purchasing a new unit which, because of the simplicity of construction of the device, he 45 may put in the radiator himself in the place of the defective unit.

The invention is further designed to provide a radiator composed of a plurality of independent units which are readily removable and replaceable so that little time is 50 taken up in repairing the radiator.

The invention further consists in the several features hereinafter set forth and more particularly defined by claims at the conclusion hereof.

In the drawings:

Figure 1 is a front view of the device embodying the invention, parts being broken away and parts being shown in section;

Fig. 2 is a section taken on line 2—2 of 60 Fig. 1;

Fig. 3 is a section taken on line 3—3 of Fig. 1;

Fig. 4 is a section taken on line 4—4 of Fig. 1;

Fig. 5 is a detail sectional view of one of the radiator units.

In general, the device comprises a supporting frame, upper and lower tanks secured to the frame, and a plurality of independent removable radiator units communicating with the upper tank and the lower tank. The upper tank forms the supply tank for the radiator units and the lower tank constitutes the outlet from said units 75 and connections are also provided for connecting up the radiator to the circulating system for cooling the engine.

The frame consists of upright supporting members or plates 6 which may be secured 80 to any suitable support, as the side frame members of an automobile and means for connecting the supply and outlet tanks to said members. This means comprises an upper plate 7 which is secured at its sides 85 8 to the upper portion of the members 6 in any suitable manner, as by rivets 9, and which is provided with a back portion 10 having a pipe connection 11 formed therein for securing one of the pipes in the circulating system (not shown) thereto, and a lower plate 12 which is secured at its sides 90 13 to the lower portion of the members 6 in any suitable manner, as by rivets 14, and which is provided with a back portion 15 95 having pipe connections 16 formed therein for connecting up some of the pipes in the circulating system (not shown) thereto.

The upper or supply tank or reservoir 17 is secured to the upper plate 7 by bolts 18 100 which pass through apertures 19 in the sides of the tank and through sleeves 20 within the tank, secured thereto by soldering or otherwise to make the tank water tight, and which bolts also pass through a rubber 105 gasket 21 secured at the back side of the tank and through apertures 22 in the back portion 10, said bolts being secured to the back of the plate 7 by nuts 23. The gasket 21 is provided with an aperture 24 in com- 110

unication with the pipe 11 and the tank 17 with an inlet 25 communicating with the pipe 11, through the aperture 24. The tank 17 is provided with a filler opening 17' and 5 with a plurality of feeding channels 26 formed by depending side portions 27 of the bottom of the tank, and a transversely extending notched filler plate 28 secured thereto to form a water tight compartment. 10 These channels have oppositely disposed outlets 29.

The lower outlet or collecting tank or conduit 30 is secured to the lower plate 12 by bolts 31 which pass through apertures 15 32 in the sides of this tank and through sleeves 33 within the tank, secured thereto by soldering or otherwise to make the tank water-tight, and which bolts also pass through a rubber gasket 34 secured at the 20 back side of the tank and through apertures 35 in the back portion 15, said bolts being secured to the back of the plate 12 by nuts 36. The gasket 34 is provided with apertures 37 adjacent the pipe connections 16 25 and the tank 30 is provided with apertures 38 in communication with the pipes 16 through said apertures 37. The tank is provided with a plurality of inlet channels 39 formed by upwardly projecting portions 30 40 of the top of the tank and a notched filler plate 41 similar to the plate 28 secured thereto to form a water-tight compartment, said channels being preferably disposed in the central portion of the top of the tank. 35 These inlet channels 39 have a plurality of oppositely disposed inlets 42. The tank 30 also has compartments 43 formed in one of the sides thereof and a suitable form of heater, such as an acetylene gas burner 44 40 may be disposed in each of said compartments to heat the liquid in the tank during times of cold weather when there is liability of the cooling liquid freezing. Each of these burners 44 is connected to a suitable 45 source of fuel supply, not shown.

The circulating means between the upper and lower tanks comprises a plurality of independent removable radiator units 45. Each unit 45 consists of a hollow member 50 formed of one or more plates 46 to form a channel 47. For the purpose of circulating air through the units, their sides are punched in numerous places to form air channels 48. These channels 48 are formed in vertically 55 extending rows, the channels in adjacent rows being arranged in staggered relation. While the holes or small air channels 48 thus formed may be of any desired shape, I prefer to form them, as shown in Fig. 5, in 60 which there is a central orifice 49, a section of gradually decreasing capacity in the direction of air flow 50, and a section of gradually increasing capacity in the direction of flow 51. Such channels in effect 65 form small Venturi tubes and as is well

known in devices of this kind the air travels through the orifice at a greater rate than it would through a straight tube. These channels are formed by punching in sections of each side of the plate in such a way as to provide a flange 52 on one side which is crimped down adjacent the aperture made in the other side, as shown in Fig. 5. The top and bottom of each radiator unit is provided with filler pieces 53 and 54, respectively, preferably of metal secured within the hollow of the plate or plates 46 by soldering. The top filler piece and the sides of the plates are provided with a notch or channel 55 and the lower filler piece and the sides of the plates with a notch or channel 56 which channel, through means hereinafter described, communicates with the upper and lower feed channels 26 and 39, respectively. Thus the filler pieces provide solid ends for each of the units and the channels therein communicate with the hollow 47 of the unit. 70 75 80 85

From the foregoing description it will be noted that the channel 47 formed by the plate or plates 46 and provided with the upper and lower filler pieces and the air channels extending through the broad sides thereof form an independent radiator unit and means are provided for detachably securing each of these units in position within the radiator and in communication with the upper and lower tanks thereof. It will be further noted that, as the channels 55 and 56 extend inwardly, either end of the unit 100 may be used as the top or bottom. 90 95

This means comprises a plurality of bolts 57 which pass through apertures 58 in the sides of the units and the upper and lower filler pieces 53 and 54 and through apertures 105 in the sides of the reservoir and outlet conduit and the upper and lower filler plates 28 and 41, the units being strung on these bolts and disposed between the upper and lower tank, as shown in Fig. 2, and being 110 spaced from each other by apertured washers 59, the plates being tightly held against the washers and also against the inwardly extending portions of the reservoir and tank by nuts 60. 115

The radiator units may be of any desired size or shape, but I preferably make them of flat rectangular shape and arrange them transversely of the radiator in a plurality of spaced apart rows, as shown in Fig. 1, 120 and connect up a plurality of units in each row, as shown in Fig. 2. By this arrangement it will be noted that in addition to the air channels in the units themselves, I form an air space between each of the rows of 1 units and between each of the units in a row and thus provide for an efficient circulation of air to cool the water or liquid passing through the radiator. 125

The units are assembled, as shown in Fig. 13

2, a washer 59 being interposed between adjacent units at the top and bottom thereof and the apertures of the washer are aligned with the channels 55 and 56 in the filler spaces and with the openings 29 and 42 of the feed channels for the upper and lower tanks. In the case of the front and back radiator units the feed channel only goes through one side of the plate 46, as shown 10 at 61 in Fig. 2.

In the construction above described the water or other cooling liquid passes from the upper tank 17 through the feed channels 26 and outlets 29 into the channels 15 formed by the washers 59 and the notches or channels in the upper ends of the units. As the cooling liquid flows along through these channels it also flows downwardly through the channels 47 in the units and is 20 subjected to the action of the currents of cooling air and thence flows along through the channels formed by the washers 59 and the notches or channels in the lower end of the units, thence through the inlets 42, into 25 the channels 39 and the outlet tank 30. The upper and lower tanks are suitably connected in the liquid cooling system connected with the cylinders of the engine.

If for any cause one of the radiator units 30 should leak, it can be readily ascertained in which row of units the leak occurs, and the units in this row may be removed by removing the bolts 57 and the leaky unit may then be readily replaced with a new one or the 35 leaky unit, if it be an intermediate one, may be removed entirely and the remaining units and accompanying washers may be moved up and the radiator will again be ready to perform its functions as the removal of an 40 intermediate unit only shortens up the row. In case the front or back units should leak and no new units were available to be substituted therefor, the outer leaky unit may be dispensed with and the intermediate unit 45 adjacent the outer unit may be utilized by plugging up the front of the upper and lower channels in the unit.

I am aware that the invention above described is capable of considerable variation

and modification and I therefore wish it understood that any construction which would come within the scope of the appended claims is within the scope of my invention.

What I claim as my invention is:—

1. As an article of manufacture, an independent radiator unit consisting of a hollow member provided with filled ends having channels extending therethrough into the hollow of said member, and having a 60 plurality of air-channels extending therethrough, each of said air-channels being of gradually decreasing capacity followed by gradually increasing capacity in the direction of flow of the air therethrough. 65

2. A radiator, for the purpose described, comprising a reservoir, an outlet conduit, a plurality of independent removable hollow radiator units having liquid conducting channels therein, apertured washers disposed between said units adjacent the ends thereof and communicating with said channels, said units being arranged in transversely extending rows with a plurality of units in each row, a series of feed channels 70 from the reservoir and outlet conduit communicating with the channels formed by the washers and the ends of the units, and means for detachably securing the units in each row in position. 75

3. A radiator, for the purpose described, comprising an upper reservoir provided with a plurality of outlets, a lower collecting tank provided with a plurality of inlets, a plurality of spaced apart hollow radiator units having solid ends provided with channels leading into the hollow of each unit, apertured washers disposed between said units and the inlets and outlets of the reservoir and collecting tank and communicating with the channels in the ends of said units, said units being arranged in a plurality of rows with a plurality of units in each row, and means passing through the solid ends of the units and through the reservoir and tank 90 to secure the units in each row in position. 95

In testimony whereof I affix my signature.
FRANK JUTRASCH.
